GARMENT BELT

Samuel Auerbach, New York, N. Y., assignor to
 Auerbach Bath Robe Co., New York, N. Y., a
 firm consisting of Samuel Auerbach, Nathan
 Auerbach, Morris Auerbach, and Edward Auer-
 bach

Application April 7, 1939, Serial No. 266,452

3 Claims. (Cl. 241—8)

This invention relates to new and useful improvements in a garment belt.

The invention has for an object the construction of a garment belt which is characterized by a strip of material having an end portion bent back of the front section thereof and secured at the said bent portion to the garment, and also secured at the other end portion to the garment so as to form a loop for the belt, and a novel arrangement for utilizing the back section of the strip of material for holding the belt from slipping out of the loop.

Still further the invention proposes the use of a detachable fastener for connecting the back section of the strip with the belt.

Still further the invention proposes a novel method for constructing the garment belt.

Another object of the invention is the construction of a garment belt as described which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

30 Fig. 1 is a front elevational view of a garment provided with a belt constructed according to this invention.

Fig. 2 is an enlarged elevational view looking in the direction of the line 2—2 of Fig. 1.

35 Fig. 3 is a perspective view similar to Fig. 2 but showing the belt in a shifted position.

Fig. 4 is a vertical sectional view taken on the line 4—4 of Fig. 3.

The garment belt, according to this invention, 40 is used in conjunction with a garment 10. A strip of material 11 has an end portion 11a bent back of the front section 11b thereof. A line of stitches 12 secures the strip of material at the bent portion to the garment 10. Another line of 45 stitches 13 secures the other end portion of the strip of material to the garment.

It is proposed that the garment 10 be provided with a seam 14 juxtaposed beneath the strip of material 11. This seam 14 is produced by inter-engaging edge portions 14a of the parts used to make the garment and sewing these inter-engaged portions together with lines of stitches 15. The stitches 12 and 13 are arranged transversely across the seam 14 for the reason that due

to the reinforced character of the seam the garment is strongest at this area.

A belt 16 for the garment is engaged through the loop produced by the strip of material 11. The back section 11a is arranged against the back face of the belt 16. A detachable fastener 17 is mounted upon the adjacent face of the belt 16 and the back section 11a for detachably connecting these parts together. This fastener 17 may be a standard snap fastener. The bottom end of 10 the front section 11b of the strip of material is provided with a bent in area 11bb. The stitches 13 are engaged through this bent in area. This is for the purpose of doubling the material of the strip at the area at which it is attached to the 15 garment and thus producing a stronger construction.

The garment may be provided with several of the loops and associated construction as illustrated in Fig. 3. A feature of the construction 20 resides in the fact that the belt 16 is held by the loops and is held by the back section of the loops against accidental complete displacement from the loops. At the same time the belt is free to shift a limited distance through the 25 loops, which is desirable when the garment is worn and the belt tied about the waist of a person.

The method of manufacturing the garment belt consists in first bending the upper end portion 30 of the strip of material 11 to produce the rear section 11a and then securing the strip of material upon the garment by sewing to produce the stitches 12 and 13. One section of the fastener 35 may be mounted upon the back section 11a of the strip of material before or after it is mounted in position upon the garment. The other section of the fastener is mounted on the belt 16 before or after it is positioned on the garment.

While I have illustrated and described my 40 invention with some degree of particularity, I realize that in practice various alterations therein may be made. I therefore reserve the right and privilege of changing the form of the details of construction or otherwise altering the arrangement of the correlated parts without departing from the spirit or the scope of the appended claims.

Having thus described my invention, what I claim as new and desire to secure by United 50 States Letters Patent is:

1. In combination with a garment, a vertical strip of material having its top end portion bent back of the front section thereof and secured at said bent portion to said garment so that the 55

- back section of the strip freely depends and said strip being also secured at its bottom end portion to said garment so as to form a loop for a horizontal belt, a horizontal belt engaging through said loop, and a fastener connecting said back section with said belt, whereby the belt may shift forwards and rearwards by swinging said depending portion.
2. In combination with a garment, a vertical strip of material attached at its ends to said garment so as to form a loop for a belt, a back strap of material beneath said loop and attached at its top end only so that it freely depends, a horizontal belt engaging through said loop, and a fastener connecting the free end of said back strap with said belt, whereby the belt may shift forwards and rearwards by swinging said depending portion.
3. In combination with a garment, a vertical strip of material having its top end portion bent back of the front section thereof and secured at said bent portion to said garment so that the back section of the strip freely depends and said strip being also secured at its bottom end portion to said garment so as to form a loop for a horizontal belt, a horizontal belt engaging through said loop, and a fastener connecting said back section with said belt, whereby the belt may shift forwards and rearwards by swinging said depending portion, said garment being made of sections and having a seam with overlapping portions of garment material, and said strip of material being juxtaposed on said seam. 10 15

SAMUEL AUERBACH.
